UNITED STATES PATENT OFFICE

FRANK KUSTERLE, OF KENOSHA, WISCONSIN, ASSIGNOR TO SIMMONS COMPANY, OF NEW YORK, N. Y., A CORPORATION OF DELAWARE

HOSPITAL TABLE

Application filed February 9, 1931. Serial No. 514,408.

This invention relates to an improved hospital table construction and has particular reference to an improved arrangement for vertically, adjustably mounting a table top 5 on a supporting structure. The invention also has reference to a hospital table embodying a main table structure including a main table top, an auxiliary table top, and a mounting such as above referred to, for the latter, 10 whereby the auxiliary top is also rotatably adjustable horizontally relative to said main table top.

The main objects of the invention are, to provide a vertically adjustable table structure which is positive in its action and not 15 apt to slip or become out of order; to provide such adjusting mechanism which is easy to operate, so that a hospital patient confined to a bed can operate the same without great 20 exertion; to provide an adjusting mechanism located within a hollow supporting post; to provide such an arrangement which does not adversely affect the generally neat outside 25 appearance of the structure; to provide, in a hospital table structure embodying a main supporting structure and a table top adjustable to over-the-bed or offset position relative to said main supporting structure, means 30 for preventing tipping of the structure when the auxiliary top is in such offset or over-balancing position; and, in general, it is the object of the invention to provide an improved hospital table structure of the type referred to.

Other objects and advantages of the invention will be understood by reference to the following specification and accompanying drawings (two sheets) illustrating a hospital table of the type referred to, and certain de- 40 tails of its construction.

In the drawings:

Fig. 1 is a plan;

Fig. 2 is a side elevation;

Fig. 3 is a section on the line 3—3 of Fig.

45 1, and

Figs. 4 and 5 are sections on the lines 4—4 and 5—5, respectively.

Referring now to the drawings, my improved hospital table comprises a main table 50 top 10 and main supporting frame 11 to

which the main table top 10 is secured. The structure also embodies an auxiliary table top 12 which is carried by a supporting post 13, the latter being rotatably mounted on the main frame 11 and provided with a laterally offset foot portion 14 disposed beneath the auxiliary table top 12, substantially as shown in Fig. 2, for the purpose of preventing over-balancing of the structure when the auxiliary top is in the offset or over-the-bed position 55 illustrated in full lines. As indicated by broken lines in Fig. 2, the auxiliary table top 12 is mounted so as to be swingable about a vertical axis to a position overlying the main table top 10.

The supporting post 13 is preferably in the form of a square metal tube and it is rotatably mounted on the main frame 11 by means of vertically spaced bearings 15 and 16. The bearings 15 and 16 may be of substantially like construction, the details of 60 which are illustrated in Figures 3 and 4.

By inspection of Figs. 3 and 4, it will be seen that the bearings in which the post 13 is rotatably mounted comprise strap metal 75 members 17 bent to form a substantially circular loop, the ends of the strip being turned outwardly to form ears 18, 18. The bearing member 17 is adapted to be mounted on the main frame 11 by screws or rivets such as 80 indicated at 19, which pass through the ears 18 and secure the loop member to a bracket 20, the bracket member 20 extending between two of the legs of the frame and being secured to said legs in any suitable manner. Bearing cups, such as indicated at 21, are secured 85 to the post 13 by brazing or otherwise, and these cups 21 are of such size as to rotatably fit within the loop 17. A cover plate 22 may be provided for closing the cup-like bearing member 21. As shown, the upper portion of the bearing member 21 is turned outwardly to form a flange designed to rest on the upper edge of the loop member 17 to thereby 90 support the post against downward movement through the member 17 in the event that the table structure as a whole is lifted from the floor when being moved, or for any other purpose.

The auxiliary table top 12 may be of any 100

suitable construction and preferably includes a frame 23 and an intermediate cross bar 24, these parts being covered with a sheet metal or other suitable cover element 25. At one 5 side, the auxiliary top 12 is provided with a bracket element 26, this bracket being secured to the auxiliary table top in any convenient manner. In this instance, it is illustrated as being secured to the table top by 10 means of a stem or shank 27 formed integral with the bracket 26 and fitting through openings provided in the frame 23 and projecting into the intermediate cross member 24. These parts may be secured together by welding, 15 brazing, or in any other appropriate manner.

The bracket 26 also embodies a depending hollow part 28 which is designed to receive the upper end of a square tube or sleeve 29, 20 the hollow part 28 being provided with an internal stop flange 30 for limiting insertion of the sleeve 29. A set screw 31 may conveniently be utilized for detachably securing the sleeve 29 to the hollow part 28 of the 25 bracket.

The sleeve 29 is elongated to provide the desired range of vertical adjustment for the auxiliary table top and it fits slidably within the hollow post 13.

30 For adjusting the auxiliary table top vertically relative to the supporting post 13 and main table top 10, and for holding the auxiliary table top in the desired position of relative adjustment, a screw device is provided. 35 This device consists of an elongated screw 32 disposed inside of the sleeve 29 and rotatably mounted at its upper end, as indicated at 33, in the upper end of the bracket 26. A handle 34 is secured to the reduced upper end 40 portion of the screw, for instance, by means of a cross pin 35. The screw 32 is thus rotatably but axially fixed in the bracket 26 and relative to the auxiliary table top and the handle 34 obviously serves to facilitate rotation of the screw.

45 For co-operating with the screw 32 within the sleeve 29 and post 13, a nut 36 is provided, this nut being non-rotatably secured in a tube or other suitable support 37 which 50 is secured by means of a cross pin 38 at its lower end to the hollow post 13. The tube or nut support 37 extends upwardly from the cross pin 38 to support the nut 36 adjacent the top of the post 13. The tube 37 may conveniently be another square tube, and the 55 nut 36 may be square in cross section to fit the tube so as to be non-rotatable therein. Also, the nut may be provided with an external flange 39 at its upper end for engaging 60 the upper end of the supporting tube 37, whereby the nut is held against downward movement. Preferably, but not necessarily, the nut 36 is a tight fit in the tube 37, or secured thereto so as to be not readily withdrawn therefrom.

It will now be apparent that by rotating the screw 32, the auxiliary table top 12 will be adjusted vertically, inasmuch as the screw is axially fixed relative to the auxiliary table top, while the nut with which the screw operates is axially fixed with respect to the supporting post 13. The lower end of the screw 32 is desirably provided with a reduced shank portion 40, free from threads, for free rotation within the nut 36. Hence, in the event that the screw 36 is turned to such an extent that the threaded portion of the screw is turned out of the nut, the shank 40 will remain therein and constitute a guide for restoring co-operative engagement between the 75 screw and nut upon proper rotation of the screw.

In the drawings, I have illustrated the hollow post 13, the sleeve 29 and the nut support 37 as being telescopically fitting tubes. It is, however, to be understood that in the commercial embodiment of the described structure, these tubes need not be of accurate interfitting relationship, but should be freely slidable relative to each other, so that resistance to vertical adjustment of the auxiliary table top will be of a minimum amount and, as a practical matter, no greater than is incident to the weight of the adjusted parts. Obviously, the screw-and-nut arrangement 95 will serve to hold the auxiliary top in the desired position of adjustment, it being understood that the pitch of the screw threading is not sufficient to permit rotation of the screw within the nut solely by reason of the weight 100 of the screw and parts supported thereby.

I am aware that changes may be made in the above described structure without departing from the spirit of the invention, the scope of which should be determined by reference 105 to the following claims, the same being construed as broadly as possible consistent with the state of the art.

I claim as my invention:

1. In a hospital table, the combination of 110 a table top, a hollow post for supporting said top, means for vertically, adjustably mounting said top on said post comprising a nut disposed inside of said post and mounted therein so as to be non-rotatable and supported against downward movement, a screw mounted on said table top so as to be rotatable in axially fixed position relative thereto, said screw depending from said table top and into said post and having co-operative engagement with said nut, whereby the table top is vertically adjustable as an incident to rotation of the screw, and a handle disposed above said table top and connected to said screw for facilitating manual rotation thereof. 115

2. In a hospital table, the combination of a 120 main table top and a supporting frame therefor, an auxiliary table top, a hollow post rotatably mounted on said supporting frame for 125

- rotatably supporting said auxiliary table top, means for vertically, adjustably mounting said auxiliary table top on said rotatably mounted post including a screw-and-nut device disposed inside of said post, said auxiliary top being thereby horizontally adjustable from a position overlying said main table top to an offset position outside of the area of said main table top, and also vertically 5
 10 adjustable relative to said main table top, and an offset foot carried by said rotatable post in fixed relation thereto, said foot underlying said auxiliary top for engaging the floor outside of the area of the main frame to prevent 15 overbalancing of the table when the auxiliary top is adjusted to said offset position.
 3. In a hospital table, the combination of a main table top, a supporting frame for said main table top, an auxiliary table top, a hollow post rotatably mounted on said main frame, a sleeve depending from said auxiliary top and fitting telescopically into said post, a rotatable but axially fixed, elongated screw depending from said auxiliary table top within 20
 25 said sleeve, a nut disposed inside of said sleeve for co-operating with said screw to effect vertical adjustment of said auxiliary top incident to rotation in the screw, and means inside of said post for non-rotatably supporting said nut adjacent the upper end of said post and against downward movement therein.
 4. In a hospital table, the combination of a main table top, a supporting frame for said main table top, an auxiliary table top, a hollow post rotatably mounted on said main frame, a sleeve depending from said auxiliary top and fitting telescopically into said post, a rotatable but axially fixed, elongated screw 30
 35 depending from said auxiliary table top within said sleeve, a nut disposed inside of said sleeve for co-operating with said screw to effect vertical adjustment of said auxiliary top incident to rotation of the screw, and means inside of said post for non-rotatably supporting said nut adjacent the upper end of said post and against downward movement therein, said screw having a reduced lower end portion adapted to turn freely inside of 40
 45 said nut out of co-operative engagement with the threads thereof.
 5. In a table structure, the combination of a table top, a hollow post for supporting said top, a sleeve depending from said top and fitting telescopically into said post, a screw and nut device within said sleeve and post, one of the parts thereof being carried by said table top and the other by said post, said posts being in cooperative engagement inside of said 50
 55 post, and means whereby said device is manually operable to thereby effect vertical adjustment of the table top relative to the post.
 6. In a table structure, the combination of a table top, a hollow post for supporting said top, a sleeve depending from said top 60
 65
- and fitting telescopically into said post, a screw and nut device within said sleeve and post, one of the parts thereof being carried by said table top and the other part by said post, the part carried by said post being secured thereto below the lower end of said sleeve and extending upwardly into said sleeve for co-operative engagement with the other part within the sleeve. 70
